CLAIM

The ornamental design for a combination telephone,
clock, radio, lamp, and memo tray, as shown and de-
scribed.

DESCRIPTION

FIG. 1 is a top, front, left side perspective view of a
combination telephone, clock, radio, lamp, and memo
tray showing my new design;

FIG. 2 is a top plan view thereof;

FIGS. 3 and 4 are respectively left and right side eleva-
tional views thereof;

FIGS. 5 and 6 are respectively front and rear eleva-
tional views thereof;

FIG. 7 is a bottom plan view thereof; and,

FIG. 8 is a top, front, left side perspective view thereof,
with the lamp raised and the memo tray extended.

The telephone cord is partially shown in broken lines
for convenience of illustration.

FIG. 2

FIG. 3

FIG. 4

FIG. 5

FIG. 6

FIG. 7
